UNITED STATES PATENT OFFICE

2,441,123

STEAM GENERATOR

Edward E. Weed, East Port Chester, Conn.

Application November 19, 1937, Serial No. 175,520

Section 3, Public Law 690, August 8, 1946
Patent expires November 19, 1957

5 Claims. (Cl. 122—451)

1

This invention appertains to new and useful improvements in steam generators and more particularly to an apparatus especially adapted for use in tailoring shops, and which in use could be adapted as a heating plant for buildings and elsewhere.

An important object of the invention is to provide a steam generator wherein both the feed water and fuel lines are cut off at a predetermined steam pressure.

Another important object of the invention is to provide a generator of the character stated wherein the feed water is automatically turned on after the coil has been preheated.

These and various other important objects and advantages of the invention will become apparent to the reader of the following specification.

In the drawings:

Figure 1 represents a side elevational view of the apparatus.

Figure 2 is a top plan view showing the coil case in section.

Figure 3 is a fragmentary vertical sectional view through the water line control valve.

Figure 4 is a vertical sectional view through one of the valves.

Figure 5 is a fragmentary detailed sectional view through the lower portion of the thermostatic unit.

Figure 6 represents perspective views of the water and gas control rods.

Referring to the drawings wherein like numerals designate like parts, it can be seen in Figure 1 that numeral 5 represents a case in which the boiler or generator coil 6 is located.

Under the coil is the burner 7 of the usual liquid fuel type and adjacent this is the pilot 8 having the supply line 9.

Numeral 10 denotes the fuel supply pipe line, while numeral 11 denotes the water pipe supply line. In the line 10 is the valve generally referred to by numeral 12, while in the line 11 is the valve generally referred to by numeral 13. These valves are automatic valves and close at a predetermined pressure in the coil 6.

Each of the lines 10—11 has a manual valve therein and these manual valves are generally referred to by numerals 14—15, respectively. Each of the valves 14—15 is provided with a control stem having an arm at its upper end and these arms are denoted by numerals 16—17 respectively.

Numeral 18 denotes an elongated control rod on which an eye member 19 of a rod 20 is slid-

2

able. On the rod 18 is a coiled compressible spring 21 interposed between the eye 19 and the anchoring member 22.

As can be seen in Figure 1, a case 23 is provided on the side of the coil 6 and this has a thermostatic element 24 therein controlling a catch rod 25. This catch rod 25 operates a member 26 which is engageable with a notch 27 in the rod 18.

10 As can be seen in Figure 2, the rod 18 in one end is connected to the arm 17 while the rod 20 is connected to the arm 16, the arm 16 projecting from the inner end of the hand lever 28 and this arm 28 is operative over the gage frame 15 29.

Obviously when the hand lever 28 is moved to the left in Figure 2, the spring 21 is placed under pressure, while the fuel valve 14 is opened, so that the burner 7 is set in operation.

20 When the coil 6 has become sufficiently heated, the thermostat 24 will release the rod 18 so that the spring 21 will operate the rod 18 to open the valve 15.

A branch pipe 30 is tapped from the upper portion of the coil 6 and opens into both the valves 12—13 located in the pipe lines 11—10.

As is clearly shown in Figure 3, each of these valves 12—13 consists of a shell 31 having a plug 32 in one end thereof and being screw connected as at 33 to the T-fitting 34. One side of the water line as shown in Figure 3 is connected to the nipple 35 while the other side is connected to the portion 36 of the T-fitting 34 and also extending from this fitting 34 is the tube 37. This tube 37 is a small tube in circumference compared with the pipe 11 and has a small orifice 38 at its end adjacent the coil 6. In this manner, water from the water line is supplied directly to the coil area from the valve 13.

40 The valve 13 has a valve seat 39 and the valve element 40 operative thereon. This valve element 40 has the stem 41 connected at its upper end to the piston 42 operative in the shell 41 and against the action of the spring 43. The aforementioned steam branch pipe 30 connects the top of this valve 13 as well as the valve 12 and when a certain pressure has been reached in the coil, these valves 40 are forced downwardly closing off the supply of the water and fuel.

45 While the foregoing specification sets forth the invention in specific terms, it is to be understood that numerous changes in the shape, size and 50 materials may be resorted to without departing

from the spirit and scope of the invention as claimed hereinafter.

Having described the invention, what is claimed as new is:

1. Control mechanism for a steam generator having a boiler, a burner, and a pair of supply lines to said boiler and burner, respectively, said mechanism comprising a pair of valves in said lines, respectively, a thermostatic device responsive to temperature variations in the generator, a lever for opening the valve of the line to the burner settable to opening position, and means conditioned by such setting of said lever for subsequent operation under control of said device to open the other valve.

2. Control mechanism for a steam generator having a boiler, a burner, and a pair of supply lines to said boiler and burner, respectively, said mechanism comprising a pair of valves in said lines, respectively, a thermostatic device responsive to temperature variations in the generator, a lever for opening the valve of the line to the burner settable to opening position, and means conditioned by such setting of said lever for subsequent operation under control of said device to open the other valve, said means comprising a member movable to open said other valve, devices on said member and thermostatic device, respectively, normally coacting to releasably lock said member against movement, a spring adapted for compression to move said member, and means operative by setting of the lever to compress said spring.

3. Control mechanism for a steam generator having a boiler, a burner, and a pair of supply lines to said boiler and burner, respectively, said mechanism comprising a pair of valves in said lines, respectively, a thermostatic device responsive to the temperature variations in the generator, a lever for opening the valve of the line to the burner settable to opening position, means conditioned by such setting of said lever for subsequent operation under control of said device to open the other valve, and means for closing both of said lines under a predetermined steam pressure in said boiler.

4. Control mechanism for a steam generator

having a boiler, a burner, and a pair of supply lines to said boiler and burner, respectively, said mechanism comprising a pair of valves in said lines, respectively, a thermostatic device responsive to temperature variations in the generator, a lever for opening the valve of the line to the burner settable to opening position, and means conditioned by such setting of said lever for subsequent operation under control of said device to open the other valve, said means comprising a rod endwise movable to open said other valve, a member adapted to interlock with said rod to prevent such movement thereof and operative by said thermostatic device to break said interlock, a spring adapted for compression to move said rod, and means operative by setting of said lever to compress said spring.

5. Control mechanism for a steam generator having a boiler, a burner, and a pair of supply lines to said boiler and burner, respectively, said mechanism comprising a pair of valves in said lines, respectively, a thermostatic device responsive to temperature variations in the generator, a lever for opening the valve of the line to the burner settable to opening position, and means conditioned by such setting of said lever for subsequent operation under control of said device to open the other valve, said means comprising a rod endwise movable to open said valve, a member adapted to interlock with said rod to prevent such movement thereof and operative by said thermostatic device to break said interlock, a coil spring sleeved on said rod for compression to move the same, and means operative by setting of said lever to compress said spring including a second rod connected at one end to said lever and having the other end thereof slidably connected to the first-mentioned rod.
